OVERLOAD RELEASE MECHANISM

Floyd R. Nelson, Rockford, Ill., assignor to Cotta
Transmission Corporation, Rockford, Ill., a cor-
poration of Illinois

Application September 6, 1940, Serial No. 355,701

20 Claims. (Cl. 192—150)

This invention relates to a new and improved overload release mechanism for electric motor-driven devices, as, for example, motor-driven domestic stokers.

In the past, stokers have ordinarily been equipped with shear pin type release mechanisms, but these have been objectionable because of the added work connected with replacing the shear pin when the stoker has been automatically shut off by reason of jamming of the feed screw. It is therefore the principal object of my invention to provide a release mechanism of a simpler and more economical construction wherein the drive is disconnected in the event of excessive resistance to turning of the driven shaft of the feed screw driving transmission and the motor circuit is also automatically broken to stop the motor, the mechanism being devoid of any shear pin but having instead a kick-out member which requires only resetting after it is kicked out due to the overload, the resetting being as simple as pressing a button.

Another important object of the invention consists in incorporating the kick-out member in the belt driven pulley where the manually operable resetting pin or knob thereon is easily accessible.

Still another object consists in providing the motor switch in a housing arranged to be mounted in proximity to the pulley where a rotary pendant switch-operating member carried by the housing is arranged to be struck by the reset pin only when the kick-out member has been kicked out, whereby to open the switch. The pendant member when swung upwardly is arranged to be locked releasably in the open circuit position by a latch member one side of which bears against the spring-pressed plunger of the switch and the other side of which has a detent notch therein to accommodate the pendant member in the raised open circuit position. The latch member is arranged to be tripped manually to release the pendant member after the kick-out member has been reset and everything is in readiness for restarting the motor.

The invention is illustrated in the accompanying drawings, in which—

Fig. 1 is a longitudinal vertical section through the drive pulley portion of a stoker drive transmission showing the overload release mechanism of my invention, the switch-operating mechanism being shown in this view in vertical section on the line 1—1 of Fig. 5 and the pulley being in section on the broken line 1—1 of Fig. 3;

Fig. 2 is a section similar to a portion of Fig. 1, showing the motor switch-operating mechanism in vertical section in the plane of the line 2—2 of Fig. 6;

Fig. 3 is a view of the inner side of the pulley taken on the line 3—3 of Fig. 1 with a portion of the cover plate broken away for better illustration;

Fig. 4 is a similar view showing the kick-out member in the kicked out position;

Fig. 5 is a rear view of the switch housing indicating diagrammatically the radius of operation of the reset pin with relation to the switch-operating mechanism under normal conditions, and

Fig. 6 is a similar view indicating the larger radius of operation of the reset pin after the overload has occurred, and showing the parts of the switch operating mechanism in moved position.

The same reference numerals are applied to corresponding parts throughout the views.

Referring first mainly to Fig. 1, the reference numeral 7 designates the housing of a domestic stoker drive transmission for driving the usual coal feed screw. 8 is the driven shaft of the transmission to which is keyed, as at 9, a hub 10. A drive pulley 11 is rotatable on the bearing portion 12 of the hub 10 and is retained in place by a washer 13 and cotter pin 14. The pulley is of a stepped cone type and is adapted to receive the V belt 15 in either one of its three grooves according to the speed at which the stoker feed screw is to be driven. An electric feed motor, not shown, carries the companion stepped cone pulley over which the belt 15 passes, and it is that motor which the switch 16 hereinafter referred to controls. At 17 there is indicated generally an overload release mechanism incorporated in the pulley, in accordance with my invention, providing a driving connection between the pulley 11 and hub 10 so long as there is no abnormal increase in resistance to turning of the feed screw as reflected by a proportionate increase in resistance to turning of the driven shaft 8. 18 is the reset pin or knob projecting from the back of the pulley and normally operating on the small radius *a*, as indicated in Fig. 5, but arranged to operate on the larger radius *b*, as indicated in Fig. 6, after the overload has caused the release mechanism 17 to disconnect the pulley 11 from driving relation to the hub 10. At 19 there is indicated generally the switch operating mechanism arranged to be operated by the reset pin 18 after the pulley

has been disconnected from driving relation to the hub, whereby to open the switch 16 and stop the motor. It is well known in the stoker art how a spike, rock, or other foreign body, in the coal being fed to the stoker by the feed screw is apt to cause the screw to jam, and it is such an overload which will cause the automatic disconnection of the pulley 11 from driving relation to the hub 10. Most stokers have an obstruction clean-out plate on the end of the coal feed conduit next to the hopper where the foreign body is usually found to lodge, and once the obstruction has been removed and the stoker is ready to resume operation it is not necessary with the present invention to replace a shear pin, as in the other stokers having other types of overload release mechanisms. It is only necessary with the present invention to reset the overload release mechanism 17 by depressing the reset pin 18, which, as will soon appear, requires no more effort than pressing a push button. Then the stoker is in readiness for restarting the motor, and the switch-operating mechanism 19 includes a latch 20, which, as will soon appear, may be tripped manually to close the switch 16 and start the motor.

Referring now to Figs. 1, 3 and 4, the overload release mechanism 17 comprises a kick-out member 21 pivoted on the web portion 22 of the pulley 11, as indicated at 23. This member is elongated and carries the reset pin or knob 18 on the free end portion thereof in transverse relation thereto projecting freely through a slot 24 in a cover plate 25 fastened to the rim portion 26 of the pulley 11 as by means of screws 27, this plate having a central hole 28 provided therein through which a portion of the hub 10 projects, as clearly appears in Fig. 1. A cam projection 29 on the kick-out member 21 intermediate the ends thereof has its inclined cam surface or shoulder 30 arranged slidably to engage the cam surface or shoulder 31 on a drive pin 32 mounted in the hub 10 and projecting radially therefrom. So long as the cam projection 29 is disposed in engagement with the drive pin 32, as shown in Fig. 3, wherein the direction of rotation of the pulley 11 is indicated by the arrow c, the hub 10 is driven with the pulley and the coal feed screw of the stoker which relies for its drive upon the shaft 8 will accordingly be driven. The leaf-spring 33 mounted on the web 22 of the pulley on a stud 34 and disposed in engagement with the inner head end of an adjustable screw 35 mounted radially in the rim 26 of the pulley has a bent free end portion 36 arranged to hold the kick-out member 21 in driving position against the cam action of the projection 29 on the drive pin 32 tending to kick out the member 21 toward the position shown in Fig. 4, wherein the free end portion of the kick-out member 21 is disposed in engagement with the extreme outer end portion 37 of the leaf-spring 33 in engagement with a stop 38 provided by the end portion of the spring which is bent approximately at right angles toward the kick-out member. The bent portion 36 of the leaf-spring 33 is so inclined in relation to the rounded free end 39 of the kick-out member and extends transversely relative to the path of movement of the end portion of the kick-out member so that a certain predetermined force is required to move the kick-out member 21 outwardly against the resistance of the spring 33, this force being, on the other hand, many times greater than that required to return the kick-out

member, due to the fact that there is no shoulder on the leaf-spring obstructing the return movement and only slight deflection of the spring 33 is required, as should be clear from a study of Fig. 4. The pin or knob 18 projects sufficiently from the pulley 11, as clearly appears in Fig. 1, so that it is easy to press inwardly on it in the direction of the shaft 8 to reset the kick-out member 21 from the position of Fig. 4 to the position of Fig. 3. By adjustment of the screw 35 inwardly toward the spring 33, the force required to kick out the member 21 against resistance of the bent end portion 36 of the spring 33 can be greatly increased, while, on the other hand, outward adjustment of the screw away from the spring 33 will decrease the force necessary to kick out the member 21. In that way, it is a simple matter to set the release mechanism 17 to disengage the pulley 11 from driving relation to the hub 10 within a certain range above the normal resistance to turning of the shaft 8, so that on the one hand there will be no danger of the coal feed screw drive being disengaged due to a slight fluctuation in the amount of power required to turn the feed screw, and on the other hand there will be no question in regard to the positive disconnection of the drive when a spike, rock, or other serious obstruction, causes jamming of the feed screw. The screw 35 will, of course, be properly adjusted at the stoker manufacturer's plant and should not require readjustment thereafter. A lock nut 40 on the screw is arranged to be tightened against the rim 26 of the pulley to secure the screw in its adjusted position.

Referring now principally to Figs. 2, 5 and 6, attention is again called to the fact that the pin 18 under normal driving conditions moves in a circle having the small radius indicated at a in Fig. 5, whereas upon disconnection of the pulley 11 from driving relation to the shaft 8 by reason of the kicking out of the member 21, due to unusually great resistance to the turning of the shaft 8, the pin 18 in the subsequent free turning of the pulley 11 moves in a circle having the larger radius b, indicated in Fig. 6. The switch 16, previously mentioned, is mounted within a housing 41 suitably secured to the housing 7 of the stoker drive transmission, as indicated at 42 in Figs. 1 and 2. Electrical conductors for the motor driving the pulley 11 are extended through conduit entered in the hole 43 in one side of the housing 41 in proximity with the switch 16. The switch 16 may, of course, be of any suitable or preferred type, but is preferably of a snap action type to snap "on" and "off" having a spring-pressed plunger 44 tending normally to move outwardly toward closed circuit position but arranged to be moved inwardly to open circuit position by the latch 20, previously mentioned, forming a part of the switch-operating mechanism 19. The latch is pivoted at one end inside the housing 41 on a pin 45 and engages the plunger 44 intermediate its ends, the free end portion of the latch extending through a slot 46 in the top wall of the housing so as to provide a handle portion for convenient manual operation of the latch. The latch has a notch 47 therein on that side thereof opposite the place where the plunger 44 at the switch 16 engages the latch. 48 is a rotary pendant member which also forms a part of the switch-operating mechanism 19. The pendant member 48 is in the form of a generally C-shaped rod pivotally mounted by its horizontal upper end portion 49

in bearings 50 provided therefor in the housing 41, the member 48 normally hanging vertically with the lower horizontal end portion 51 thereof disposed in the same vertical plane in which the reset pin 18 moves but slightly above the circle of movement, as indicated in Fig. 5. However, when the member 21 is kicked out to the position shown in Fig. 4, causing the reset pin 18 to move in the circle of larger radius, as indicated in Fig. 6, the pin 18 in the rotation of the pulley will strike the lower end portion of the pendant member 48 and cause it to swing upwardly toward engagement in the notch 47 in the latch 20. Usually the speed at which the pin 18 strikes the pendant member 48 is enough to cause the latter to swing upwardly with sufficient force on the very first encounter to engage in the notch 47. At any rate, the second or third revolution of the pulley after it has been disconnected from the hub 10 will certainly result in the pin 18 striking the pendant member 48 hard enough to move the latter to the full line position shown in Figs. 2 and 6. In the upward swinging movement of the pendant member 48, the bent end 52 slides along the straight edge 53 of the latch member 20, moving the latter from the inclined dotted position, shown at *d* in Fig. 2, to a substantially vertical position slightly to the right of the full line position of Fig. 2, but when the end 52 of the pendant member 48 rides into the notch 47, the latch 20 moves to the left under the action of the spring-pressed plunger 44, gripping the pendant member in the raised horizontal position. In the movement of the latch member 20 from the dotted line position *d* of Fig. 2 and finally to the full line position of Fig. 2, the plunger 44 of the switch 16 is moved to the right enough to snap the switch to "off" position, breaking the circuit for the motor driving the pulley 11. Promptly thereafter the pulley 11 stops and everything remains at a standstill until the spike or other obstruction which caused the feed screw to jam is removed. Then, the reset pin 18 is depressed to move the kick-out member 21 back to driving position, whereupon the latch 20 is moved to the right just enough to release the pendant member 48 holding the switch 16 in open circuit position. Then, upon release of the latch 20, the plunger 44 moves outwardly under spring action causing the switch 16 to snap to closed circuit position so as to restart the electric motor driving the pulley 11. It is obviously a much simpler matter to manipulate the reset pin 18 and latch 20 than to replace a shear pin. Replacement of a shear pin invariably required calling a service man, whereas the average stoker owner can by observance of simple instructions take care of everything from clearing out the obstruction at the feed screw to restarting the motor.

It is believed the foregoing description conveys a good understanding of the objects and advantages of my invention. The appended claims have been drawn with a view to covering all legitimate modifications and adaptations.

I claim:

1. A combination overload release mechanism and motor switch operating mechanism comprising, in combination, a motor driven drive member, a driven shaft having a drive hub thereon relative to which the drive member is adapted to turn freely, a drive projection on the hub, a kick-out member movably mounted on the drive member having a drive projection thereon arranged to engage the aforesaid drive projec-

tion on the hub to transmit drive from the drive member to the shaft, said drive projections being formed to have a cam action with respect to one another so that the kick-out member is moved from normal drive position when there is more than a predetermined resistance to turning of the shaft, a reset pin on the kick-out member projecting from the drive member for manual resetting purposes, a switch for controlling a motor circuit, and means for operating the switch operable upon engagement therewith by the reset pin, said pin being inoperative in relation to said means in the normal position of the kick-out member.

5 15 20 25 30 35 40 45 50 55 60 65 70 75

2. A structure as set forth in claim 1, including spring means for holding the kick-out member in driving position, and screw threaded adjusting means for varying the spring action so that more or less resistance to turning of the driven shaft will result in movement of the kick-out member from driving position.

3. A structure as set forth in claim 1, wherein the last mentioned means comprises a swingable pendant member arranged to be struck by the reset pin to swing it upwardly from a normal dependant position to operate the switch to open circuit position, and manually releasable latch means for releasably locking the pendant member in a raised position so as to keep the switch in open circuit position until manual release of the latch means.

4. An overload release mechanism for a drive train, comprising in combination a drive member, a driven shaft having a drive hub thereon relative to which the drive member is adapted to turn freely, a drive projection on the hub, a kick-out member movably mounted on the drive member having a drive projection thereon arranged to engage the aforesaid drive projection on the hub to transmit drive from the drive member to the shaft, said drive projections being formed to have a cam action with respect to one another so that the kick-out member is moved from normal drive position when there is more than a predetermined resistance to turning of the shaft, and a leaf spring slidably engaging a portion of said kick-out member to hold it releasably either in driving position or inoperative position, the kick-out member being movable manually from inoperative to driving position.

5. An overload release mechanism for a drive train, comprising in combination a drive member, a driven shaft having a drive hub thereon relative to which the drive member is adapted to turn freely, a drive projection on the hub, a kick-out member movably mounted on the drive member having a drive projection thereon arranged to engage the aforesaid drive projection on the hub to transmit drive from the drive member to the shaft, said drive projections being formed to have a cam action with respect to one another so that the kick-out member is moved from normal drive position when there is more than a predetermined resistance to turning of the shaft, a reset pin on the kick-out member projecting from the drive member for manual resetting purposes, spring means for holding the kick-out member in driving position, and screw threaded adjusting means for varying the spring action so that more or less resistance to turning of the driven shaft will result in movement of the kick-out member from driving position.

6. An overload release mechanism for a drive train, comprising in combination a rotary drive member and a rotary driven member in coaxial

relationship, one of said members having a substantially radial cam-shaped drive projection, an elongated kick-out member pivotally mounted at one end on the other of said members having a cam-shaped drive projection intermediate its ends arranged slidably to engage the first projection, whereby drive is transmitted from the driving to the driven member, and a leaf spring detent cooperating with the free end of the kick-out member to hold the latter normally in drive position, the free end of the kick-out member being slideable past the detent portion of the leaf spring against resistance of the spring when there is more than a predetermined resistance to turning of the driven member.

7. A structure as set forth in claim 6, wherein the leaf spring detent is of elongated form and rigidly supported at one end, the detent portion being adjacent the other free end, and wherein the free end portion of said leaf spring is formed to provide a stop projection beyond the detent portion to limit movement of the free end portion of the kick-out member relative to said leaf spring in the kick out movement.

8. A structure as set forth in claim 6, wherein the leaf spring detent is of elongated form and rigidly supported at one end, the detent portion being adjacent the other free end, and wherein the free end portion of said leaf spring is formed to provide a stop projection beyond the detent portion to limit movement of the free end portion of the kick-out member relative to said leaf spring in the kick out movement, and manually operable means for moving the kick-out member back to drive position.

9. A structure as set forth in claim 6, wherein the leaf spring detent is of elongated form and rigidly supported at one end, the detent portion being adjacent the other free end, and wherein the free end portion of said leaf spring is formed to provide a stop projection beyond the detent portion to limit movement of the free end portion of the kick-out member relative to said leaf spring in the kick out movement, and screw threaded adjusting means cooperating with the leaf spring to adjust the tension thereof relative to the kick-out member and accordingly make it more or less easy for the kick-out member to be kicked out.

10. In a motor drive connection for a motor driven device, the combination of a housing for said device, a driven shaft extending therefrom, a drive pulley arranged to be driven by a belt from an electric drive motor, a hub drivingly connected with the shaft and rotatably mounting said pulley, the side of said pulley toward the housing providing a recess annularly with respect to the hub, means providing a shoulder on the hub, an elongated kick-out member pivoted at one end to the pulley in said recess and having a drive lug projecting therefrom intermediate its ends for engagement with the driving shoulder, the driving shoulder and lug being formed for sliding camming engagement relative to one another so as to cause the kick-out member to be 65 swung outwardly relative to the hub, spring detent means resisting outward movement of the kick-out member, a reset pin projecting from the kick-out member in substantially parallel relation to the driven shaft, a motor switch adapted to control the electric circuit for the aforesaid motor driving the pulley, a housing for said switch mounted on the first mentioned housing adjacent the pulley, a pendant member for operating the switch pivotally mounted on the 75

housing and hanging with the lower end thereof normally out of the path of movement of the reset pin but within the path of movement thereof when the kick-out member is kicked out, and 5 manually releasable latch means for releasably locking the pendant member in a raised position with the switch held thereby in open circuit position.

11. A structure as set forth in claim 10, including screw threaded adjustable means for adjusting the tension of the spring detent means relative to the kick-out member, substantially as and for the purpose described.

12. A structure as set forth in claim 10, where- 15 in the spring detent member comprises an elongated leaf spring rigidly supported at one end and having a detent portion on the other free end portion thereof arranged to be slidably engaged by the free end portion of the kick-out member, said spring being formed at the free end thereof to provide a stop projection for engagement by the kick-out member in the kicked out position, said leaf spring serving yieldingly to hold the kick-out member in such position.

13. An overload release mechanism comprising, in combination with relatively rotatable driving and driven members, a kick-out element oscillatably mounted on one of said members for movement to and from driving position, the kick-out element having a cam-shaped driving projection arranged to have sliding engagement with a cam surface provided on the other of said members so that the kick-out element is moved from normal driving position when there is more than a predetermined resistance to turning of the driven member, an elongated leaf spring mounted at one end on the same member with the kick-out element and having sliding engagement with a portion of said element at its other end to hold the element releasably either in driving position or inoperative position, said kick-out element being movable manually from inoperative to driving position, and screw-threaded adjusting means on the same member with the kick-out element and leaf spring having engagement with the leaf spring at a point intermediate the ends thereof to increase or decrease the pressure of said leaf spring on the kick-out element.

14. A drive control mechanism comprising, in combination with relatively rotatable driving and driven members, a kick-out element oscillatably mounted on one of said members for movement to and from driving position, the kick-out element having a driving projection arranged to have sliding engagement with a surface provided on the other of said members, an elongated leaf spring mounted at one end on the same member with the kick-out element and having sliding engagement with a portion of said element at its other end to hold the element releasably either in driving position or inoperative position, said kick-out element being movable manually from inoperative to driving position, and screw-threaded adjusting means on the same member with the kick-out element and leaf spring having engagement with the leaf spring at a point intermediate the ends thereof to increase or decrease the pressure of said leaf spring on the kick-out element.

15. An automatic control mechanism comprising, in combination, an oscillatable kick-out member, an elongated leaf spring rigidly supported at one end and having a stepped free end portion for sliding engagement with the free end

of the kick-out member to hold it releasably on one step in operative position or on another step in inoperative position, the kick-out member being movable manually from inoperative to operative position, and screw-threaded adjusting means having engagement with the leaf spring at a point intermediate the ends thereof to increase or decrease the pressure of the stepped end portion of said leaf spring on the kick-out member.

16. In a motor drive connection for a motor driven device, the combination of a housing for said device, a driven shaft extending therefrom, a drive pulley arranged to be driven by a belt from an electric drive motor, a hub drivingly connected with the shaft and rotatably mounting said pulley, the side of said pulley toward the housing providing a recess annularly with respect to the hub, means providing a driving shoulder on the hub, an elongated kick-out member pivoted at one end to the pulley in said recess and having a drive lug projecting therefrom intermediate its ends for engagement with the driving shoulder, the driving shoulder and lug being formed for sliding camming engagement relative to one another so as to cause the kick-out member to be swung outwardly relative to the hub, spring detent means resisting outward movement of the kick-out member, a reset pin projecting from the kick-out member in substantially parallel relation to the driven shaft, and impact operated circuit control means for controlling the electric circuit for the aforesaid motor driving the pulley, said means being arranged to be struck by the reset pin when the kick-out member is kicked out.

17. A structure as set forth in claim 16, including screw-threaded adjustable means for adjusting the tension of the spring detent means relative to the kick-out member, substantially as 40 and for the purpose described.

18. A structure as set forth in claim 16, wherein in the spring detent member comprises an elongated leaf spring rigidly supported at one end and having a detent portion on the other free end portion thereof arranged to be slidably engaged by the free end portion of the kick-out member, said spring being formed at the free end thereof to provide a stop projection for engagement by the kick-out member in the kicked out position, said leaf spring serving yieldingly to hold the kick-out member in such position.

19. An impact operated circuit control means comprising, in combination with impact means rotatable with a rotary member, a swingable pendant member on an adjacent support arranged to be struck by said impact means to swing it upwardly from a normal dependent position to a switch operating position, a switch operable by said pendant member in raised position, and manually releasable latch means for releasably locking the pendant member in raised position.

20. An impact operated circuit control means comprising, in combination with impact means rotatable with a rotary member, a swingable pendant member on an adjacent support arranged to be struck by said impact means to swing it upwardly from a normal dependent position to a switch operating position, a switch having a spring-pressed plunger tending normally to move outwardly toward one extreme position but arranged to be moved inwardly to another extreme position when the pendant member is swung upwardly, and a latch member for releasably locking the pendant member in raised position while holding the plunger of said switch in the last-named extreme position, the spring pressure on said plunger causing said latch member to grip the pendant member resiliently.

FLOYD R. NELSON.
